Letters Patent

Spiced Feb. 25, 1807.

The Schedule referred to annexed making part of the said Letters Patent, containing a Description in the Words of the said joel Stoy junr. himself of his machine for working a Trip Hammer with the handle, in a perpendicular position.

This machine consists of a Frame nine feet long, six feet wide and eight feet high braced at top and bottom, four and a half, a large shaft with a cog-wheel, an wild Cat on which is four Cams, a Slider, & a Spring: the parts five & a half feet high, on which is placed a shaft, on which are a cog-wheel and a crank, an anvil, Hammer, and a hammer handle with one Cam. The large shaft & the Slider are placed parallel on the beams of the frame; the crank is turned by a water-wheel; the cog of the crank shaft connect with the cog of the large shaft, & turn that shaft. The cams of the wild Cat on that shaft catch the cam of the Hammer handle as the shaft turns, & raise the Hammer four times at one turn of the shaft; the spring is riveted upon one end of the Slider & extends thence to the upper end of the Hammer-handle, with which it is connected, and serves to force the Hammer upon the iron with a suitable degree of velocity. This machine may be enlarged or diminished, and an addition made to or deducted from any of its parts as will be best suited to the stream of water by which it may be worked, & will be the best calculated to facilitate the manufacture of the different materials which may be wrought in it. —
